(57) **CLAIM**

The ornamental design for a device for cooling or heating, as shown and described.

DESCRIPTION

FIG. 1 illustrates a top front perspective view of a device for cooling or heating a human or other mammal, the device employing an ornamental design in accordance with the present invention;

FIG. 2 illustrates a bottom rear perspective view thereof;

FIG. 3 illustrates a top plan view thereof;

FIG. 4 illustrates a bottom plan view thereof;

FIG. 5 illustrates a first side elevation view thereof;

FIG. 6 illustrates a second side elevation view thereof, wherein it is opposite of FIG. 5;

FIG. 7 illustrates a front elevation view thereof;

FIG. 8 illustrates a rear elevation view of the thereof; and, FIG. 9 illustrates a top front perspective view of the device of FIG. 1 but with two portions of the device pulled apart to allow placement around a neck of the human or other mammal.

The broken lines are included for the purpose of illustrating unclaimed portions of the device and form no part of the claimed design.
